4 Claims. (Cl. 181—49)

This invention relates to exhaust mufflers for internal combustion engines and more particularly to a simplified and effective muffler for small engines such as are used in compressors, starters, lawnmowers, and the like.

In the development of such small engines, simplicity and economical manufacture without sacrificing quality are highly important, and it will be noted that many small engines lack mufflers entirely while many others have mufflers that are either ineffective, expensive, easily damaged, difficult and costly to assemble and repair, or conducive to considerable back pressure if not properly constructed.

An object of the present invention is to improve small internal combustion engines by providing a simplified muffler having a minimum number of parts.

Another object of the invention is to improve small engine muffler construction by providing a muffler casing directly attachable to the cylinder head without the use of adapters or extraneous parts.

A further object of the invention is to further muffler manufacture by constructing a muffler having readily stamped parts and arranged for simple and rapid assembly to the engine.

A still further object of the invention is to improve muffler construction by providing simplified parts assembled in such a manner as to give greatest structural strength.

For a more complete understanding of the invention, reference may be had to the accompanying drawing illustrating a preferred embodiment of the invention in which like reference characters refer to like parts throughout the several views and in which

Fig. 1 is a front elevational view of the muffler assembly constructed in accordance with the invention.

Fig. 2 is an end elevational view of the muffler and a fragmentary portion of the cylinder head, and

Fig. 3 is a cross-sectional view taken substantially on the line 3—3 of Fig. 1.

An internal combustion engine cylinder head 10 is illustrated as having conventional air cooling fins 11 and an exhaust port opening 12. A muffler structure 13 is secured to the cylinder head 10 by bolts 14 or similar attaching means, and comprises a casing assembly preferably constructed of an inner plate member 15 and an outer body member 16, preferably secured together by means of a crimped edge 17 and defining an elongated muffler chamber 13a therebetween, as shown in Fig. 3.

The inner plate member 15 has an extruded pocket portion 18, in the approximate center of which is provided an inlet opening 19 arranged to register with the cylinder head exhaust port opening 12, as illustrated in Fig. 3. Also in Figs. 2 and 3 will be seen how the provision of the extruded pocket portion 18 permits the remainder of the inner plate 15 to clear the cylinder head fins 11 which are adjacent the exhaust port opening 12, thus eliminating the need for a special adapter between the muffler and the cylinder head.

The muffler body member 16 is provided with an ex-

2

haust outlet opening preferably in the form of louvered slots 25 disposed in the outer face of the body member 16 and laterally offset from the inner plate inlet port 19.

A tubular element 26, preferably cylindrical in shape and provided with perforations 26a is seated in the pocket 18 and encloses a portion of the chamber 13a immediately adjacent the inlet opening 19. The baffle element 26 preferably is substantially concentric with the center of the inlet opening 19, and extending to the outer face 10 of the body member 16 it serves as a spacer, providing support for the body member 16.

The bolts 14 extend through the outer face of the body member 16 and the pocket 18 into the cylinder head 10 adjacent the exhaust port opening 12, and are thus preferably enclosed by the baffle element 26. The baffle element 26 is spaced from the peripheral side of the body member 16 to permit unrestricted flow of exhaust gases into the chamber 13a. Exhaust flow thus is from the exhaust port opening 12 into the interior of said baffle element 26, through the perforations 26a into the muffler chamber 13a and out the openings 25.

Although we have described but one preferred embodiment of the invention, it will be apparent to one skilled in the art to which the invention pertains that various changes and modifications may be made therein without departing from the spirit of the invention or the scope of the appended claims.

We claim:

1. An exhaust muffler for an internal combustion engine having a finned cylinder head provided with an exhaust port, said muffler comprising substantially oval shaped inner and outer walls and a peripheral side wall defining a substantially flattened laterally elongated chamber, one end of said inner wall having an inlet opening 30 communicating with said exhaust port, said outer wall having an outlet opening disposed opposite the other end of said inner wall and thereby being laterally offset from said inlet opening, a tubular baffle member longitudinally sandwiched between said inner and outer walls and 35 peripherally enclosing only a portion of said chamber 40 directly adjacent said inlet opening, said baffle member comprising a tubular structure having inner and outer ends respectively abutting the inner and outer walls of said muffler whereby said baffle member is retained by 45 and between said walls, and means securing said muffler to said cylinder head, said muffler extending laterally with respect to said exhaust port.

2. The muffler as defined in claim 1 and in which said inner wall comprises a substantially flat oval face plate 50 having an axially outwardly extruded pocket in the end having said inlet opening, said pocket directly abutting said cylinder head at the exhaust port whereby the remainder of said face plate overlies and is closely spaced with respect to the cylinder head fins adjacent said exhaust 55 port.

3. The muffler as defined in claim 2 and in which the inner end of said baffle member is seated in said pocket and has a peripheral edge contacted by the inner periphery of said pocket, said pocket thereby preventing lateral 60 displacement of said baffle member.

4. An exhaust muffler for an internal combustion engine having a finned cylinder head provided with an exhaust port, said muffler comprising substantially oval shaped inner and outer walls and a peripheral side wall 65 defining a substantially flattened laterally elongated chamber, one end of said inner wall having an inlet opening communicating with said exhaust port, said outer wall having an outlet opening disposed opposite the other end of said inner wall and thereby being laterally offset from said inlet opening, a tubular baffle member longitudinally sandwiched between said inner and outer walls and 70

peripherally enclosing only a portion of said chamber directly adjacent said inlet opening, and means securing said muffler to said cylinder head, said muffler extending laterally with respect to said exhaust port, said inner wall comprising a substantially flat oval face plate having an axially outwardly extruded pocket in the end having said inlet opening, said pocket directly abutting said cylinder head at the exhaust port whereby the remainder of said face plate overlies and is closely spaced with respect to the cylinder head fins adjacent said exhaust port, the inner end of said baffle member being seated in said pocket, said pocket thereby preventing lateral displacement of said baffle member, and said baffle comprising a substantially cylindrical perforated element disposed substantially concentric with the center of said inlet opening, said means securing said muffler to said cylinder head comprising bolts extending through said outer wall and said pocket into said cylinder head, said baffle element extending from said pocket to said outer wall and serving

5 to support same against deformation on tightening said bolts.
